ELECTROMEDICAL APPARATUS

Eugenie Leibowitsch-Berge, London, England

Application June 25, 1947, Serial No. 757,007
In Great Britain January 10, 1947

2 Claims. (Cl. 128—406)

1

This invention relates to electrical apparatus for the treatment of the skin, in which there is provided a source of pulsating current together with means for introducing intermittency in the form of low or high frequency currents, e. g. an induction coil connected to a source of electrical energy, such as a dry cell, or a main supply in conjunction with a transformer and if necessary a rectifier, and in which the low voltage direct high or low frequency currents are applied to the skin by means of "applicator" electrodes, another electrode, i. e. the "return" electrode being connected to a convenient part of the person permanently during treatment. More particularly the present invention relates to apparatus of this type intended for facial treatment, and the chief object of the invention is to provide apparatus whereby the intermittent unidirectional current may be applied by the user of the apparatus easily to various contours of the face in a highly efficacious manner. Another object of the invention is to provide a compact portable form of apparatus by which self-treatment may be effected.

According to the present invention electrical apparatus for the treatment of the skin comprises a container for the accommodation of means for connecting electrodes to the source of electrical energy in a controlled manner, and carrying a set of applicator electrodes adapted to be applied selectively to the part of the body to be treated, a handle comprising a return electrode, means to connect the applicator electrodes selectively to said return electrode, said return electrode being adapted to be held in the hand, and means carried by the return electrode to connect it and the appropriate applicator electrode in the operative circuit of the source of electrical energy.

In order that the invention may be clearly understood and readily carried into effect drawings are appended hereto illustrating an embodiment thereof, and wherein:

Figure 1 is a perspective view showing the container open with the electrodes exposed.

Figure 2 is a sectional elevation of a ball and socket type of electrode.

Figure 3 is a side elevation of a roller electrode, and

Figure 4 is a longitudinal section showing the return electrode with an applicator electrode fitted to it.

Referring to the drawings the electrical massaging apparatus comprises a box 1 having an inclined panel 2 forming an integral part of the

2

box 1 which is preferably a sheet metal box suitably ornamented at its edges by beading 3, which can also serve as the means for uniting the end walls of the top panel and front and rear walls. The box 1 is accommodated within an outer stout leather or other suitable casing 4, having a lid 5 within which are provided clips 6 for the support of the electrodes hereinafter described. A normally flush-fitting handle 7 is provided in a narrow horizontal top portion 8 of the panel 2 to enable the box 1 to be removed when it is desired to have access to its base, which in well known manner, is provided with a hinged flap closing a compartment containing a battery. A warning device in the form of an electric bulb 9 can be provided in the panel 2 for indicating when the battery requires replacing, the socket terminals for this lamp being connected by leads to spring contacts on the battery in well known manner.

The electrodes comprise a "return" electrode in the form of a metallic cylindrical handle 10 adapted to be grasped in the hand, and "applicator" electrodes, hereinafter described, which are selectively connected to the return electrode.

The return electrode has fixedly threaded into one end thereof so as to lie in smooth continuity therewith, an insulating cap 13 in which is screwed a plug 14 which is prolonged to form a screw 15 for engaging in a socket 21 of the selected applicator electrode. The return electrode 10 is connected to a lead 12 by any suitable means, e. g. by pinching the exposed end of this lead between the inner end of the insulating cap 13 and the opposed annular surface of the interior of the electrode 10, which inner end preferably takes the form of threaded boss 13' engaging in a correspondingly threaded socket in the appropriate end of the handle or return electrode 26. The screw 14 can press against the exposed end of a lead 11 as shown or be otherwise connected to this lead.

Four applicator electrodes are shown by way of example and one of them takes the form of a metallic roller 16 supported for rotation in a wide fork 17, i. e. a U-shaped fork which has a transverse dimension considerably greater than the length of each of its side limbs, the central part of this fork having extending from it a threaded socket 18 adapted to receive the threaded end 15 of the return electrode. The ends of the roller have smooth rounded edges 16' to obviate sharp edges liable to contact the skin.

Two of the applicator electrodes comprise

stylus shaped electrodes, in the form of elongated conical metallic members 19 each having a part-spherical free end 20, its other end comprising a cylindrical socket 21 adapted to thread on to the threaded extension 15 of the return electrode. These latter applicator electrodes are particularly suitable for engaging in folds of the neck or creases of the face, and by providing a set of them having different dimensions of part-spherical ends, various parts of the face and neck can be treated intimately by direct engagement therewith of the electrodes.

The latter mentioned part-spherical ends of the elongated conical stylus-like electrodes can vary in diameter as from e. g. $\frac{1}{16}$ of an inch to $\frac{1}{8}$ of an inch in diameter, this being a convenient range of size for the desired treatment. However, it is also desirable to produce smooth pressure and rolling over larger areas than is obtainable by the part-spherical ends of the aforesaid electrodes, and consequently another electrode is provided also having a socket 21 (see Figure 2) threaded for receiving the screw-threaded end 15 of the handle 10 and flared into a relatively larger diameter ball head taking the form of part-spherical cup 22 in which is accommodated substantially more than half of a metallic ball 23 so that a smooth rolling action is obtained. The cup 22 can include an annular cap 22' screwed or pressed upon the body portion which is integral with the part containing the socket 21. The ball 23 is pressed against the mouth of the cap 22' by a spring 24 between which and the ball 23 are interposed friction reducing balls 23'.

If desired, the applicator electrodes 19 can have straight axes co-axial with the threaded end of the handle 10; or if desired as shown, and as in fact is preferred, the stems of these electrodes can be cranked approximately midway between the ends thereof so the ball head is offset laterally relatively to the axis of the handle, this being found to be convenient in obtaining access to certain parts of the face and neck.

For the treatment of the hair an applicator electrode is provided in the form of a metal comb 24, the back of which is attached at one end to a socket 21 adapted to be fitted upon the threaded end 15 of the handle 10.

The leads 11 and 12 of the return electrode are connected to plugs 11' and 12' carried by a common insulator 10' which plug into socket terminals 25 and 26 respectively of the panel 2, these terminals 25 and 26 being connected in well known manner to a battery and induction or medical coil. A rotary control member 27 is provided for the aforesaid induction coil.

I claim:

1. A combined applicator and return electrode device for use in electrical apparatus for the treatment of the skin comprising, a return electrode formed as a metal rod-like conducting handle portion with an axial bore terminating at one end in an enlarged concentric socket, an insulating cap with a boss fixed in said socket, a bore in said cap co-extensive with the aforesaid bore and socket and enlarged at its front end to form a socket, a terminal member fixed in the latter socket and having an exposed threaded front end part, an applicator electrode detachably threaded to said threaded front end part, a sheathed lead passing along the first mentioned bore and having an exposed end pressed into engagement with the socketed part of the handle portion, and another sheathed lead passed through both of said bores and having an end exposed in the socket of said cap and engaged with said terminal member.
2. A combined applicator and return electrode device for use in electrical apparatus for the treatment of the skin, comprising a cylindrical metal rod with an axial bore, a socket in one end of the rod formed in prolongation with said bore, an insulating cap of the same diameter as the said rod and having a concentric boss screwed into said socket so that the said insulating cap lies in continuity with the said metal rod, a bore through said cap formed in continuity with the said bore of the metal rod, a socket in the end of the cap remote from the metal rod, a terminal plug screwed at one end in said cap socket and threaded at its other end, an applicator electrode threaded at one end on to the latter end of the said terminal plug, a sheathed lead threaded along the bore of the said metal rod and exposed at an end terminating in the socket of the metal rod and pressed into electrical connection with the metal rod by the boss of the said cap, and a further sheathed lead passed through both of the said bores and having an exposed end in the socket of the said cap and engaged with the said plug terminal.
